GUARD FOR THE ROTATING PORTIONS OF
AIR-MOVING DEVICESCarl M. Buttner, Memphis, Tenn., assignor to
Hunter Fan and Ventilating Company, Mem-
phis, Tenn., a corporation of Tennessee

Application March 30, 1950, Serial No. 152,779

4 Claims. (Cl. 230—275)

1

This invention relates to improvements in air-moving devices. More particularly this invention relates to improvements in guards for the rotating portions of air-moving devices.

It is therefore an object of the present invention to provide an improved guard for the rotating portions of air-moving devices.

The problem of guarding the rotating portions of air-moving devices against contact with the fingers, hands, or other portions of the anatomies of persons adjacent to such air-moving devices is one that has perplexed manufacturers of air-moving devices for many years. A large number of different kinds, sizes and shapes of guards for air-moving devices have been proposed, and a number of those guards have been used. However, many of those guards for air-moving devices fail to give sufficient protection against contact with the rotating portions of the air-moving devices, while other of those guards unduly restrict the flow of air to the rotating portions of those air-moving devices. Still other of those guards for air-moving devices are unduly expensive to manufacture and to mount. For these various reasons prior guards for air-moving devices are objectionable. The present invention obviates these objections by providing a guard which includes a number of turns of wide flat strip. Such a guard can have sizable spacing between the adjacent turns of the strip while giving full protection against contact with the rotating portions of the air-moving device, because such a guard will exclude everything except elongated, axially-aligned objects of small, uniform cross-section. Such a guard will have ample strength, and yet it will present minimum resistance to the flow of air to the air-moving device. It is therefore an object of the present invention to provide a guard for air-moving devices which includes a number of turns of wide flat strip.

The turns of the wide flat strip of the guard provided by the present invention act to channel the air into the air-moving device, and thus they tend to eliminate the eddying of air commonly noted adjacent the intake areas of air-moving devices. In addition, the turns of the flat wide strip will resist the tendency of the air, entering the air-moving device, to move angularly of the axis of the air-moving device. In doing these things the turns of the wide flat strip tend to increase the efficiency of the air-moving device.

The guard provided by the present invention includes a continuous, wide, flat strip which is

2

wound in the form of a spiral. The wide, flat strip is made of a springy metal and it will be dimensioned so it will, when removed from the mandrel on which it is wound, automatically assume the desired spiral. Such a wide, flat strip is exceedingly economical to manufacture and to mount, because it does not require precise interfitting of a number of individual parts; that strip being a single unit. It is therefore an object of the present invention to provide a guard which has a continuous, wide, flat strip of springy metal and which can be wound on a mandrel so it will, when released, assume the desired spiral.

The guard provided by the present invention includes the continuous, wide, flat strip in the form of a spiral and a number of radially-directed supporting bars. These bars not only support the continuous, wide, flat strip but they also support the driving motor of the air-moving device. In this way, the guard obviates any need for a separate mounting for the driving motor of the air-moving device. In doing this, the guard provided by the present invention offers minimum resistance to the flow of air to the air-moving device. It is therefore an object of the present invention to mount the driving motor and the continuous wide, flat strip of an air-moving device on radially-directed bars.

Other and further objects and advantages of the present invention should become apparent from an examination of the drawing and accompanying description.

In the drawing and accompanying description a preferred embodiment of the present invention is shown and described, but it is to be understood that the drawing and accompanying description are for the purpose of illustration only and do not limit the invention and that the invention will be defined by the appended claims.

In the drawing, Fig. 1 is a rear elevational view of an air-moving device that is incorporated in a window fan and that embodies the principles and teachings of the present invention, and

Fig. 2 is a sectional view of a part of the air-moving device and window fan shown in Fig. 1.

Referring to the drawing in detail, the numeral 10 denotes the frame of a window fan. The frame 10 has a Venturi ring 12 located at the approximate center thereof, and that ring will pass air while the rest of the frame 10 acts as a baffle. A number of radially-directed bars 14 are secured to the frame 10 adjacent the Venturi ring 12 by rivets 16 or other fastening devices; and the radially-directed bars 14 extend inwardly toward the housing 20 of the driving motor of the

air-moving device. The inner ends of the radially-directed bars 14 have openings therethrough, and those openings receive rivets 19 or other fastening devices. The rivets 19 also extend through openings in brackets 17 that project outwardly from the motor housing 20; the brackets 17 being solidly secured to the motor for the air-moving device. In this way, the fastening devices 16 and 19 coact with frame 10, brackets 17 and bars 14 to hold the motor of the air-moving device fixed relative to the frame 10. The radially-directed bars 14 are bent to have a V-shaped cross section. Such a cross-section strengthens those bars while reducing the overall width of those bars; thus reducing their resistance to the passage of air.

A continuous, flat, wide strip 18 is supported by the radially-directed bars 14; and that strip forms a spiral which extends from the inner ends of the bars 14 to the outer ends of those bars. The various turns of the spiral are all spaced apart equal distances. The spiral formed from the strip 18 has a conical configuration; each turn of the spiral extending rearwardly of the next-outermost turn of said spiral. The spiral formed from strip 18 overlies the annular space between the motor housing 20 and the Venturi ring 12 of the frame 10; and in doing so it protects the hands, fingers and other portions of the anatomies of persons, as by keeping them from contacting the rotating portion of the air-moving device. That rotating portion carries a number of blades 22 which will cause air to move through the Venturi ring 12 when the motor is operating.

The continuous strip 18 is secured to the rear surfaces of the bars 14; and it is preferably secured to each of those bars by welding. In forming the continuous strip 18, a flat, wide strip of springy metal of the proper length is selected, and it is wound on a mandrel of such size that, when released, the strip 18 will automatically assume the desired spiral. The formation of the spiral in this way makes it unnecessary to interfit a number of parts and then secure them to a support; it only being necessary to weld the radially-directed bars 14 to the various turns of the strip 18. In assembling the strip 18 with the bars 14, it has been found quite simple and quite desirable to use a grooved aligning fixture for the strip 18 which has the correct conical configuration, has the required precise spacing between adjacent turns of the spiral, and has guides for the bars 14. With such a fixture it is exceedingly easy to place the preformed spiral on the fixture, press the turns of the spiral into the grooves of the fixture, place the bars 14 in the guides therefor, and spot weld the bars to the spiral. By attaching the aligning fixture to the spot welding device, the entire operation can be made semi-automatic. The saving in time and cost through use of such a guard is considerable; amounting to a saving on each guard of thirty cents (\$.30) in labor cost alone.

The radially-directed bars 14 not only support the continuous strip 18 but they also support the motor housing 20. This is very desirable because it eliminates all need for a separate support for the motor and thus minimizes the number and area of obstructions to the flow of air to the air-moving device.

In one preferred form of the invention, the strip 18 is made from a flat strip of metal that is one half (1/2) of an inch wide and is five one hundredths (.05) of an inch thick; and each of the turns of the spiral formed by that strip is spaced

one half (1/2) of an inch from the turns adjacent to it. Each turn of the spiral will extend approximately two tenths (0.2) of an inch rearwardly of the turn disposed outwardly of it. The use of a strip with a width that equals the spacing between the turns of the spiral is very desirable because it makes possible the use of a large spacing between the turns of the spiral without increasing the risk to the fingers, hands, or other portions of the anatomies of individuals. The flat, wide strip does this by preventing the passage of objects to the air-moving device except when the objects are directly aligned with the axis of the air-moving device, when those objects are of small, uniform cross sections, and when those objects are long enough to extend through the guard and extend to the rotating portion of the air-moving device. The wide spacing between adjacent turns of the guard reduces the area occupied by the material of the guard and thus minimizes the guard's resistance to the flow of air. The conical configuration of the guard is desirable because it prevents straight-line, radial movement of air or physical objects through the guard.

The turns of the strip 18 are all aligned with the axis of the air-moving device. As a result, the guard tends to channelize the air moving to the air-moving device; and this is desirable for two reasons: first, it tends to minimize eddying and turbulence of the air adjacent the rear of the blades 22, and second, it tends to keep the air passing to the blades 22 from moving angularly of the axis of the air-moving device. In doing these things, the guard provided by the present invention increases the efficiency of operation of the air-moving device.

The frame 10 of the air-moving device is provided with extensible wings 24 that can be telescoped outwardly from that frame to fit wide window frames. Those wings can, of course, be retracted until they are adjacent the frame 10 so they can fit the frames of narrow windows. Wing nuts 26 coact with bolts extending through openings in the wings 24 and frame 10 to hold the wings 24 against undesired movement.

Whereas a preferred embodiment of the present invention has been shown and described in the drawing and accompanying description it should be apparent to those skilled in the art that various changes may be made in the form of the invention without affecting the scope thereof.

What I claim is:

1. A guard that is adapted to be used adjacent an air-moving device that has a driving motor and a supporting frame and that comprises a continuous flat, wide strip of metal wound in a spiral, a frame to support said driving motor, said motor-supporting frame being at the center of said spiral and being the inner terminus of said spiral, said motor-supporting frame being a ring, and a plurality of radially-extending bars supporting said strip and said motor-supporting frame, each of said radially-extending bars extending from the motor-supporting frame of said air-moving device to the supporting frame of said air-moving device and being secured to and supporting every turn of said spiral, said strip having a number of widely spaced turns that have their wide faces directed axially of said spiral.
2. A guard that is adapted to be used adjacent an air-moving device that has a driving motor and a supporting frame and that comprises a continuous flat, wide strip of metal wound in a spiral, a frame to support said driving motor,

said motor-supporting frame being at the center of said spiral and being the inner terminus of said spiral, said motor-supporting frame being a ring, and a plurality of radially-extending bars supporting said strip and said motor-supporting frame, each of said radially-extending bars extending from the motor-supporting frame of said air-moving device to the supporting frame of said air-moving device and being secured to and supporting every turn of said spiral, said strip having a number of widely spaced turns that have their wide faces directed axially of said spiral, the spacing between adjacent turns of said strip being approximately equal to the width of said strip.

3. A guard that is adapted to be used adjacent an air-moving device that has a driving motor and a supporting frame and that comprises a continuous flat, wide strip of metal wound in a spiral, a frame to support said driving motor, said motor-supporting frame being at the center of said spiral, and a plurality of radially-extending bars supporting said strip and said motor-supporting frame, said strip having its narrowest surface secured to said radially-extending bars and having its widest surface spaced from said radially-extending bars, each of said radially-extending bars extending from the motor-supporting frame of said air-moving device to the supporting frame of said air-moving device, said strip having a number of widely spaced turns that have their wide faces directed axially of said spiral, the turns of said strip forming a cone extending between said frame and said motor.

4. A guard that is adapted to be used adjacent an air-moving device that has a driving motor

and a supporting frame and that comprises a continuous flat, wide strip of metal wound in a spiral, and a plurality of radially-extending bars supporting said strip, said radially-extending bars extending from the driving motor of said air-moving device to the supporting frame of said air-moving device, said strip having a number of widely spaced turns that have their wide faces directed axially of the motor of said air-moving device, said guard being conical in configuration, each of the turns of said strip having the trailing edge thereof spaced slightly rearwardly of the trailing edge of the next-outermost turn of the strip but having its leading edge spaced forwardly of the trailing edge of said next-outermost turn of the strip, said rearward disposition of said turns being such that the turns of said strip prevent a straight-line radial path through said guard at right angles to the axis of said spiral.
